UNITED STATES PATENT OFFICE.

JAMES EDMUND DEEVERS, OF KEENE, CALIFORNIA.

COMBINED TABLE AND DESK.

1,231,860.

Specification of Letters Patent.

Patented July 3, 1917.

Application filed February 8, 1916. Serial No. 76,930.

To all whom it may concern:

Be it known that I, JAMES EDMUND DEEVERS, a citizen of the United States, residing at Keene, in the county of Kern and State of California, have invented new and useful Improvements in Combined Tables and Desks, of which the following is a specification.

This invention relates to a combined table and desk.

It is the object of this invention to provide a combined table and desk in which the desk portion may be raised and lowered in relation to the table and when in its lowermost position to dispose the top of the desk portion flush with the top of the table portion and thereby form a continuous table top.

Another object is to provide means for raising and lowering the desk portion.

A further object is to provide a mechanism for raising and lowering the desk portion with means for automatically locking the desk portion in its uppermost position, said raising and lowering mechanism and locking means being operable from the front of the table.

Other objects will appear hereinafter.

The invention is illustrated in the accompanying drawings in which:

Figure 1 is a view of the combined table and desk showing the desk portion thereof in its elevated position.

Fig. 2 is a plan view of same.

Fig. 3 is a transverse sectional view showing the desk portion in its lowermost position.

Fig. 4 is a similar view showing the desk portion in its elevated position and illustrating the manner of raising and lowering same and showing the means for locking it in its uppermost position.

More specifically, 6 indicates the legs, 7 the side rails, and 8 the end rails of the table. A table top 9 is carried by the legs and rails and extends throughout the length of the table in the usual manner, but terminates short of the rear edge thereof, forming an open space bounded on the ends by the rails 8 and on the sides by the rail 7 and the rear edge of the table top panel.

The present invention resides in a desk portion 10 disposed in the open space and adapted to be raised and lowered in relation to the table, and in means for operating this

desk portion. The desk portion 10 is formed with a top panel 11 which is adapted to lie flush with the table top 9 when the desk portion is in its lowermost position, as shown in Fig. 3, and to be supported by the table. Mounted on the under side of the panel 11 is a housing which consists of end walls 12, a back wall 13, and a bottom wall 14, the latter being adapted to extend flush with the upper face of the table top 9 when the desk portion 10 is in its uppermost position. The space incased by the panel 11 and walls 12, 13 and 14 may be partitioned off and divided, as occasion may require, being here shown as fitted with end compartments formed by partitions 15 and as having a shelf 16 above which pigeon holes 17 and drawers 18 are provided. The interior of this housing is accessible from the front of the table when the desk portion is in its uppermost position.

Arranged beneath the rear edge of the table top 9 is a panel 19, which is pivoted at its lower edge to the end rails 8. This panel 19 serves a double purpose, namely, forming a closure for the open side of the housing when the desk portion is in its lowermost position, and serving as a latch for locking and supporting the desk portion in its uppermost position. A spring 20 bears against the upper portion of the panel 19 and tends to normally dispose the latter in a slightly canted position with its upper edge projecting beyond the rear edge of the table top 9, as shown in Fig. 4. A rod 21 connects with the panel 19 and extending through the front rail 7 is fitted with a hand-hold 22 by means of which the panel 19 may be drawn forward in opposition to the spring 20. The hand-hold 22 serves as a stop to limit the rearward movement of the panel 19.

Mounted on the under side of the wall 14 is a pair of brackets 23 which extend into and are vertically slidable in channels 24 formed on the back of the panel 19. The bottom walls of the channels 24 are inclined, thus forming the channels deeper at the bottom than at the top so that when the desk portion is moved upwardly, the brackets 23 will crowd the panel 19 forwardly and when the desk portion is in its uppermost position, the panel 19 will be moved beneath the brackets 23 to support the desk top in its uppermost position, as shown in Fig. 4.

Various mechanisms may be employed for raising and lowering the desk portion but

the preferred means for effecting this operation consists of a rock-shaft 25 disposed beneath the table top 9 and carried by brackets 26 arranged adjacent the end rails 8. This 5 rock-shaft is formed with parallel arms 27 at its ends which extend rearwardly and pivotally connect with the lower ends of links 28 depending from pivot pins 29 on the end walls 12. The rock-shaft 25 is formed with 10 a U-shaped crank 30, the open portion of which is spanned by a bracket 31 which is connected at its ends to the rock-shaft on opposite sides of the crank and which forms a fulcrum support for a lever 32. A spring 15 33 having one end rigidly connected to the crank 30 and its opposite end attached to the lever 32 forward of its fulcrum point, operates to normally maintain the outer end of 20 the lever in contact with the under side of the forward rail 7. Normally, the crank 30 extends rearwardly at a slight angle to the vertical, as shown in Fig. 3, when the desk portion is in its lowermost position with the inner end of the lever 32 adjacent the connected 25 portion of the crank.

As a means for guiding the desk portion in its vertical movement the ends thereof are fitted with guide bars 34 which slidably extend into guide channels 35 formed in the 30 rear table legs 6; the guide bars 34 being of such length as to project into the guide channels when the desk portion is in its uppermost position.

In the operation of the invention, when it 35 is desired to elevate the desk portion from its lowermost position, as shown in Fig. 3, to its uppermost position, shown in Fig. 4, the lever 32 is depressed, as indicated in dotted lines in Fig. 4, thereby turning on the 40 bracket 31. The inner end of the lever engages the connected portion of the U-shaped crank 30 and advances the latter toward the front of the table. The arms 27 then operate through the links 28 to elevate the desk 45 portion 10, which, in moving upwardly, causes the panel 19 to retract in opposition to the spring 20, as before described. When the desk portion reaches its uppermost position the upper edge of the panel 19 passes 50 beneath the brackets 23, thus supporting the desk portion against downward movement. The lever 32 is then returned to its normal position, in which position it is maintained by the spring 33. The interior of the desk 55 portion is then accessible from the front of the table, as shown in Fig. 1.

When it is desired to conceal the desk portion, the rod 21 is pulled outwardly by the hand-hold 22 to move the panel 19 out of engagement with the desk top, which will then gravitate to its lowermost position. The desk top, in moving downwardly, will advance the crank 30 in opposition to the spring 33, which spring will then operate to 60 cushion and yieldably oppose the down- 65

ward movement of the desk portion. When the desk portion is in its lowermost position the top panel thereof is flush with the table top, thereby permitting the latter to be used as a table and at the same time closing the 70 desk against access.

Means may be provided for locking the desk in both its uppermost and lowermost positions. This means is here shown as consisting of a key controlled bolt lock 36 mounted in the table top, having a bolt which may be thrown into engagement with a keeper 37 on the top panel 11 to hold the desk portion in its lowermost position, and to engage a keeper 38 on the bottom panel 23 to lock the desk portion in its uppermost position.

The table may be equipped with drawers 39, as shown, and may be otherwise arranged and designed, as occasion may require; the essential feature being to provide the table with a movable desk portion which may be lowered into the table or elevated to project thereabove.

Various arrangements and detail construction of parts may be resorted to without departing from the scope of the invention as set forth in the appended claims.

What I claim is:

1. A combined table and desk, comprising 95 a table portion, a vertically slidable desk portion foldable within the table portion, and a pivoted panel beneath the top of the table portion adapted to swing into engagement with the bottom of said desk portion 100 to support the same when in its uppermost position.

2. A combined table and desk, comprising 105 a table portion, a vertically movable desk portion mounted thereon, and normally gravitating to its lowermost position, a lever, means operated by said lever for elevating the desk portion, and a spring pressed pivoted panel carried by the table 110 adapted to automatically engage the desk portion to retain it in its uppermost position and to close the desk portion when in its lowermost position.

3. A combined table and desk, comprising 115 a table portion, a vertically movable desk portion mounted thereon and normally gravitating to its lowermost position, a lever, means operated by said lever for elevating the desk portion, a spring pressed pivoted panel carried by the table 120 adapted to automatically engage the desk portion to retain it in its uppermost position and to close the desk portion when in its lowermost position, and means for moving said panel out of engagement with the desk portion.

4. A combined table and desk, comprising 125 a table portion, a desk portion slidably and vertically movable in relation to the table portion, normally gravitating to a lower- 130

most position within the table portion, a rock shaft, toggle link connections between said rock shaft and the desk portion, a lever for actuating the rock shaft to elevate the desk portion and a movable panel serving to close the desk portion when in its lowermost position and support same when in its uppermost position.

5. A combined table and desk, comprising a table portion, a desk portion slidably and vertically movable in relation to the table portion, normally gravitating to a lowermost position within the table portion, a rock shaft, toggle link connections between said rock shaft and the desk portion, a lever for actuating the rock shaft to elevate the desk portion, and a pivoted panel for automatically engaging the desk portion to hold it in its uppermost position forming a closure for the desk portion when in its lowermost position.

6. A combined table and desk, comprising a table portion, a desk portion slidably and vertically movable in relation to the table portion, normally gravitating to a lowermost position within the table portion, a rock shaft, toggle link connections between said rock shaft and the desk portion, a lever for actuating the rock shaft to elevate the desk portion, and means for automatically engaging the desk portion to hold it in its uppermost position, comprising a spring pressed pivoted panel carried by the table portion forming a closure for the desk portion when the latter is in its lowermost position.

7. A combined table and desk, comprising a table portion, a desk portion vertically movable in relation to the table portion normally gravitating to a lowermost position within the table portion, a rock shaft, toggle link connections between said rock shaft and the desk portion, a lever for actuating the

rock shaft to elevate the desk portion, a pivoted panel serving to close the desk portion when in its lowermost position and support same when in its uppermost position, and means whereby said panel may be manually moved out of engagement with said desk portion.

8. A combined table and desk, comprising a table portion, two pairs of legs thereon, one pair of the legs formed with guide channels, a vertically slidable desk portion, a panel hinged at its lower edge and adapted to engage the bottom of said desk portion when in its uppermost position and to close it when in its lowermost position, and means for moving the panel out of engagement with the desk portion.

9. A combined table and desk, comprising a table portion, two pairs of leg members thereon, side panels connecting the adjacent leg members, a vertically slidable desk portion downwardly extending guide bars thereon movable in one pair of leg members and a closure panel pivoted on the side panels adapted to close the desk portion when in its lowermost position and to support it when in its uppermost position.

10. In a combination table and desk, a table portion, a vertically movable desk portion carried thereby, a rock shaft carried by the table portion, toggle links connecting the rock shaft to the desk portion, a U shaped crank on said rock shaft, a bracket spanning the crank, a lever fulcrumed on said bracket, and a spring having one end rigidly connecting the crank and its opposite end attached to the lever serving to maintain the lever in its uppermost position when released irrespective of the position of the crank.

In testimony whereof I have signed my name to this specification.

JAMES EDMUND DEEVERS.
